UNITED STATES PATENT OFFICE.

WILLIAM LEWIS EVANS, JR., OF WASHINGTON, INDIANA.

HINGE.

1,412,107.

Specification of Letters Patent. Patented Apr. 11, 1922.

Application filed December 22, 1919. Serial No. 346,454.

To all whom it may concern:

Be it known that I, WILLIAM L. EVANS, Jr., a citizen of the United States, residing at Washington, in the county of Daviess and

5 State of Indiana, have invented a new and useful Hinge, of which the following is a specification.

This invention relates to a hinge of the multiple pivot lever type, designed particu-

10 larly for use with the doors of garages and other structures, for causing the doors to vanish within the garage when opened. The invention is an improvement upon the construction shown, described and claimed in

15 my Patent Number 1,367,954, dated Feb. 8, 1921.

The object of the present invention is to provide a novel hinge which, when applied to the doors of a garage, will permit the doors to close in either one of two different closed positions, an outer closed position and an inner closed position, the doors being moved to the inner closed position after the automobile is driven out, and shifted to the 20 outer closed position when the machine is within the garage. By this construction, it is possible to make use of a much shorter garage than is customary with the ordinary swinging doors.

25 A further object of the invention is the provision of a hinge which will permit the doors to vanish within the garage when opened, which doors will be unaffected by the wind, and which will not require any 30 locking arrangement to hold them in their open position.

A further object of the invention is to provide a hinge which will prevent the door from sagging; will work without noise, and 35 with little effort.

In the aforesaid patent, I have disclosed a hinge for connecting a movable member, such as a door, to a stationary member, such as a booth or other compartment, said hinge 40 comprising two pairs of arms, each pair being located respectively at the top and bottom of the door, the pair at the top being pivoted to the inside face of the door and to the top of the compartment, and the pair 45 at the bottom to the inside face of the door and the bottom of the compartment. The pivots on the door and on the compartment

are spaced apart, with the space between the pivots on the door greater than the space between the pivots on the compartment, the 55 pivots on the door being arranged on opposite sides of the vertical center of the door but nearer to the center than to the side edges of said door.

In the present construction, I have located 60 the pivots of the arms on the door at opposite sides of the vertical center of the door, and at equal distances from said center and at equal distances from the vertical side edges of the door. By this disposition of the 65 elements, the door has an elliptical movement, and describes the path of approximately half an ellipse from the outer closed position to the inner closed position by a continuous motion, and when the door is open, 70 it occupies a position at right angles to the two closed positions, and may be moved to either of said positions.

The invention will be best understood from a consideration of the following detailed description taken in connection with the accompanying drawings forming part of this specification, with the understanding, however, that the invention is not confined to any strict conformity with the showing of the 80 drawings, but may be changed and modified, so long as such changes and modifications mark no material departure from the salient features of the invention as expressed in the appended claims.

85 In the drawings:

Figure 1 represents the front view of a garage showing my improved hinge applied to the doors thereof; one of the doors being shown in its open position and the other door 90 in the inner closed position.

Figure 2 is a plan view showing the doors in their outer closed position, with the adjacent part of the garage indicated in section;

Figure 3 is a similar view disclosing the 95 doors in their inner closed position;

Figure 4 is a similar view disclosing the doors in their open position;

Figure 5 is an elevation showing one of the hinge arms with the socket plates or members by which it is mounted in position;

Figure 6 is a plan view of the same;

Figure 7 is a view on a somewhat larger scale disclosing by full and dotted lines the

progressive movement of one of the doors from its open position to its closed position.

Like reference characters indicate corresponding parts in the several figures of the drawing.

Referring to the drawing, 1 designates a garage of any approved construction, and 2 the doors thereof. It is customary in garages to have double doors, and I have disclosed 10 the ordinary construction in the drawing, but I wish it understood that the invention is as fully exemplified in a single door garage, as in one with double doors.

At the front opening or the entrance to 15 the garage, the part usually designated as a jamb, marked 3, is constructed in a somewhat peculiar manner. Instead of having a single abutment or stop for the door, it has two abutments or stops, designated, respectively, 4 and 5. These abutments or stops define or limit the inner and outer closed positions of the door. Instead of forming these abutments or stops as parts of the jamb, they may be constructed separately 25 therefrom, or in any desired manner, the only essential feature being that there should be both an inner and an outer closed position for the door, and that such closed positions should be defined or limited.

30 Each door is provided with a pair of socket plates or members 6—6, shown clearly in Figure 5 of the drawings. These socket plates or members are secured by screws, or other fastening means, to the inside face of the door. These socket members or plates have sockets or holes extending from the bottom nearly to the top, as shown. They are located on the door at opposite sides of the vertical center thereof, and at equal 35 distances from said center and also at equal distances from the vertical side edges of the door. This disposition of the socket members is essential in order to secure the results hereinafter pointed out.

45 Mounted on the floor of the garage are a second pair of socket members or floor plates 7—7, which, as indicated in Fig. 5, are located beneath the floor, so as not to obstruct the passage of the machine into and out of 50 the garage. Said socket members or floor plates have sockets or holes extending from the top downwardly nearly to the bottom. It will be noted from reference to Figs. 2, 3, 4 and 7 of the drawings, that the socket members 7 are arranged on the floor in a straight line which extends at right angles to the entrance of the garage, or at right angles to the closed position of the door being spaced apart at different distances from the 55 entrance of the garage, and they do not extend beyond either of the abutments 4 and 5, respectively. In other words, the space between the abutments is greater than the space between the floor plates. This arrangement of the socket members or floor plates is

another essential feature of the present invention.

Mounted in the socket plates or members 6 and the socket members or floor plates 7, are a pair of hinge arms which are of equal 70 length, as shown. These arms have upturned vertically disposed ends 9 to fit and turn in the sockets of the socket members or door plates 6, and downturned vertically disposed ends 10 to fit and turn in the sockets of the 75 floor plates 7, being caused to turn in said sockets as the door is moved from one position to another.

At the space separating the socket members or plates 7 on the compartment or garage is 80 less than the space separating the socket members or plates 6 on the door. By virtue of this, the arms 8 are never parallel at any period of their movement.

The construction of the hinge arms 8, the 85 socket members or door plates 6, and the front plates 7, is not materially different from what is shown in my aforesaid patent, and no claim is made herein for the specific construction of said elements.

90 It should be explained that the hinge arms with their socket members 6, 7, are duplicated at the top and bottom of each door, and this arrangement is disclosed in the drawing. With the construction as hereinbefore described, the operation will be readily understood.

95 As previously stated, the doors are capable of being closed in anyone of two positions, the outer position with the doors 100 against the abutments 4, and the inner position with the doors abutting the stops 5. The two closed positions of the door are shown in Figs. 2 and 3, respectively, Fig. 2 showing the doors in their outer position, 105 and Fig. 3 illustrating the doors in their inner position. The advantages of this construction will be manifest. When the doors are in the position shown in Fig. 3, the car 110 may be driven up close to the doors, and then the doors are caused to open inwardly to the position shown in Fig. 4, to allow the car to enter the garage. After the car is in place in the garage, the doors are then closed to the position shown in Fig. 2, with the 115 rear of the car close to the doors. This is a great convenience, for it allows the use of a much shorter garage than could be used with doors swinging in, if hung on ordinary hinges, for in such event the car would have 120 to be driven far enough in so that the doors would have room to close. In taking the car from the garage, the operation is reversed, the doors being moved from the position shown in Fig. 2 to the position disclosed in Fig. 4, and after the car has been driven out of the garage, it can be left standing close to the building and the doors closed 125 to the position shown in Fig. 3.

130 The movement of the door from one posi-

tion to another is shown in Fig. 7 of the drawings, wherein the full and dotted lines illustrate the progressive movement. The dotted line *a* shows one of the doors in its open position. In moving to the position shown in full lines *b*, the door turns on the door and floor pivots of the hinge arms, both arms moving practically together. When the door reaches the position shown by dotted lines *c*, the door is turning on the outer or door pivot of the inner arm, and the inner or floor pivot of the outer arm. At this time, the inner arm remains substantially stationary, and, in moving from the position indicated by the dotted lines *c* to the closed position of the door indicated by dotted lines *d*, the door turns wholly on the outer pivot of the inner arm and the inner pivot of the outer arm.

In moving from the inner closed position of the door to the open position, the reverse operation is followed. In moving the door from the open position to the outer closed position, substantially the same movements indicated in full and dotted lines, Fig. 7, take place, for there is no difference in the movement of the door in changing from the open position to the outer position or to the inner position.

In moving the door from one closed position to another, the door is given a continuous motion, making a movement of approximately half an ellipse, the door reaching the open position half way of its complete movement.

It will be observed from Figs. 2 and 3 that the outside of the door in the position shown in Fig. 2 becomes the inside of the door in the position shown in Fig. 3.

As shown by Figs. 2, 3, 4, and 7, when the door is opened, it can be closed to either of its closed positions, depending upon whether the car is inside or outside of the garage.

So far as I am aware, I believe that I am the first to provide a door for garages or other compartments or structures, which is adapted to be closed in two different closed positions, one an outer position and the other an inner position, and at the same time the door may be swung completely open substantially parallel with the side of the garage or compartment. This arrangement provides an ideal construction for garages, or wherever there are a number of doors which it is desired to swing in a limited space. In building garages, provision must always be made for room for the door to swing. By this construction, no such provision is necessary for, as shown in Fig. 7 of the drawings, the swinging movement of the door is prescribed.

When the doors are open in the position shown in Fig. 4, they are absolutely unaffected by the wind, and do not require

any arrangements or locking devices to hold them open.

Another desirable feature is that the door is supported by hinges fastened to each side of the center and therefore, the door cannot sag. Moreover, the movement of the door is noiseless, and may be effected with the expenditure of little effort.

To secure the results herein claimed, it is necessary that the hinges on the doors should be placed on each side of the vertical center, and that each hinge should be the same distance from the side edges of the door and the same distance from said center.

As shown in Fig. 5, the socket members or floor plates 7 are located in a recess below the floor of the garage, which floor is frequently made of concrete. By this arrangement, should the car strike either of the hinge arms, which lie close to the floor, it will not injure the same.

While stress is laid on the use of the invention for garages, it should be understood that I do not wish to be limited to the use I may make of this hinge.

Having described the invention, I claim:

1. In a hinge of the character described, the combination with a stationary member and a movable member, of a hinge for the movable member comprising a pair of arms, and means for pivoting said arms to the stationary and movable members respectively, said pivots being spaced apart, the pivots connecting the arms to the movable member being located at opposite sides of the vertical center thereof and each pivot being spaced substantially the same distance from said center and also substantially equal distance from the respective side edge of the movable member.

2. In a hinge of the character described, the combination with a stationary member and a movable member, of a hinge for the movable member comprising a pair of arms, and means for pivoting said arms to the stationary and movable members respectively, said pivots being spaced apart, the pivots connecting the arms to the movable member being located at opposite sides of the vertical center thereof and equally spaced from said center and also equally spaced from the side edges of the movable member, and the pivots connecting the arms to the stationary member being located at different distances from the movable member when closed, a line intersecting said pivots on the stationary member being substantially at right angles to the closed position of the movable member.

3. The combination with a compartment having abutments or stops, one of which is located at the entrance to said compartment and the other is spaced inwardly from said entrance, of a door member, and means for

mounting said door member so that it may be closed against either of said stops which define the inner and outer closed positions of the door.

- 5 4. The combination with a compartment having abutments or stops, one of which is located at the entrance to said compartment and the other is spaced inwardly from said entrance, of a door member, and means for 10 hingedly mounting said door member so that it may be swung in an elliptical path from one of said abutments or stops to the other, said abutments or stops defining the inner and outer closed positions of the door, one 15 of the side edges of the door member engaging with one of the said abutments or stops in one of said closed positions, while the opposite side edge engages with the other abutment or stop in the second closed 20 position.

5. The combination with a compartment having abutments or stops, one of which is located at the entrance to the compartment and the other is spaced inwardly from said 25 entrance, of a door member, and means for hingedly mounting said door member for swinging around so that one or the other of its edges will cooperate with one or the other of said abutments respectively, said 30 abutments or stops defining the inner and outer closed positions of the door, and said door when at one-half of its movement being open.

6. A garage, compartment or other structure having a door for closing an opening therein, and means for hingedly mounting the door in position so that it may be moved to close the opening in any one of two closed 40 positions, and may assume an open position 45 at right angles to said closed positions and substantially parallel with and close to the side wall of the garage or compartment, one of said closed positions being spaced inwardly from the other, and said closed positions of the door being substantially parallel with each other.

7. In a garage, compartment, or other structure, a door and means for mounting said door so that it may be moved from an 50 open position substantially parallel with the side walls of the garage or compartment, to either one of two closed positions, substantially at right angles to said side walls, said mounting means causing said 55 door to describe substantially a semi-ellipse in moving from one closed position to another, and substantially a quarter ellipse when moving from the open position to either one of the two closed positions.

- 60 8. In a garage, compartment, or other structure, a door, in combination with means for mounting the door, so that it may be moved from an open position substantially parallel with the side walls of the compartment or garage to either one of two closed 65

positions at right angles to said side walls, the movement of the door being a continuous movement, and the door being shiftable from one closed position to another, or from either closed position to an open position, 70 or vice versa.

9. The combination with a compartment having abutments or stops, one being located at the entrance to the compartment and the other spaced inwardly therefrom, 75 of a door, a pair of hinge arms, plates or socket members mounted in the floor of the compartment at points between said abutments or stops, and other plates mounted on the door on opposite sides of its vertical 80 center, whereby the door may be swung in a semi-elliptical path from one closed position to another, the abutments or stops defining the closed positions of the door.

10. The combination with a relatively stationary structure having an entrance, of a door movable from one closed position to another closed position, or to an intermediate open position, floor plates located in line with each other at different distances from said entrance, the line intersecting said floor plates being substantially at right angles to the closed position of the door, abutments defining the inner and outer closed positions of the door and located outside the line of the 95 floor plates, socket members provided on the door at opposite sides of its vertical center and at equal distances from said vertical center and also equally spaced from the side edges of the door, and hinge arms mounted 100 in the floor plates and socket members, whereby the door member may be given a substantially elliptical movement in shifting from one closed position to another and may be stopped intermediately of said two 105 positions and assume an open position.

11. The combination with a relatively stationary structure having an entrance of a door movable from one closed position to another closed position, or to an intermediate open position, floor plates located 110 at different distances from said entrance, abutments defining the inner and outer closed positions of the door and spaced apart greater than the space separating the floor 115 plates, socket members provided on the door, and hinge arms mounted in the floor plates and socket members, whereby the door members may be given substantially a semi-elliptical movement in shifting from one 120 closed position to another and may be stopped intermediately of said two positions and assume an open position.

12. A garage, compartment or similar structure having a door for closing an entrance thereto, and means for hingedly mounting said door in position, said means including a pair of hinge elements, said elements being so mounted upon the door and said structure so that the door may be 125 130

moved to close said entrance in any one of two closed positions, one of said closed positions being spaced inwardly from the other, said door being also movable to assume an 5 open position at a substantially right angle to said closed position.

In testimony, that I claim the foregoing

as my own, I have hereto affixed my signature in the presence of two witnesses.
